WINDLASS HOUSING

Fred C. Good, Philadelphia, Pa., assignor to Fred C. Good & Sons, Inc., Philadelphia, Pa., a corporation of Pennsylvania

Application January 2, 1959, Serial No. 54,028

Term of patent 7 years

(Cl. D41—1)

Fig. 1 is a perspective view of the front and one side of the windlass housing embodying my new design; and

Fig. 2 is a similar perspective view showing the side opposite that illustrated in Fig. 1.

The rear of the windlass housing shown in the drawings is substantially plain.

I claim:

The ornamental design for a windlass housing, as shown and described.
